UNITED STATES PATENT OFFICE.

HARRY C. LEONARD AND ALBERT TANGENBERG, OF GRAND RAPIDS, MICHIGAN, AS
LIGNORS TO GRAND RAPIDS REFRIGERATOR COMPANY, OF GRAND RAPIDS, MICHIGAN, A CORPORATION OF MICHIGAN.

REFRIGERATOR CONSTRUCTION.

Application filed January 4, 1923. Serial No. 610,721.

To all whom it may concern:

Be it known that we, HARRY C. LEONARD and ALBERT TANGENBERG, citizens of the United States of America, residing at Grand Rapids, in the county of Kent and State of Michigan, have invented certain new and useful Improvements in Refrigerator Constructions; and we do hereby declare the following to be a full, clear, and exact description of the invention, such as will enable others skilled in the art to which it appertains to make and use the same.

This invention relates to a refrigerator construction and is more particularly concerned with a device adapted to be mounted at the front of the ice chamber in refrigerators and which may be turned down to a substantially horizontal position when the ice chamber door is opened, allowing free entrance of ice into the chamber, being turned upwardly to a substantially vertical position, after which the door is closed, there being a seal made which prevents any escape of cold air at the lower edge portions of the door with a consequent condensation of moisture on the front of the refrigerator below the door, such condensation being very injurious to the structure and tending to cause opening of joints in the wood and rapid deterioration of the finish and construction of the refrigerator at the front. It is a primary object and purpose of the present invention to provide a construction fully capable of practically attaining the above stated ends, and one which is simple in structure and strong and durable so as to withstand the heavy service to which it may be subjected, such as the heavy weights of ice that may be applied to the structure when the ice is being placed in the ice chamber, and the shocks, jars and the like coming from the depositing of the ice thereon at such times. Many other objects and purposes than those stated will appear fully and in detail as understanding of the invention is had from the following description, taken in connection with the accompanying drawing, in which,—

Fig. 1 is a fragmentary vertical section through the ice chamber or compartment of a refrigerator, having our invention applied thereto and with the same open to receive ice.

Fig. 2 is a like view with the ice com-

partment closed and the lower portion of the door sealed against the escape of the cold air at its edges.

Fig. 3 is a fragmentary horizontal section taken substantially on the plane of line 3—3, of Fig. 2.

Fig. 4 is a like section on the plane of line 4—4 of Fig. 2.

Fig. 5 is a perspective view of the device which is applied at the front of the ice chamber or compartment to seal against the escape of air at the lower edges of the door, and

Fig. 6 is a vertical section therethrough.

Like reference characters refer to like parts in the different figures of the drawings.

The ice chamber or compartment of the refrigerator is indicated at 1, having the usual ice supporting rack 2 in the bottom thereof on which the ice 3 rests when in the refrigerator. The front 4 of the refrigerator is of usual and conventional construction, having a door opening 5 therein for a front entrance to the ice compartment, and this opening is closed by a door 6 of well known construction, including in its structure a back plate 7, though, of course the specific construction of the door may be widely varied in so far as the present invention is concerned. At the back part of the door opening 5 an inwardly extending vertical rib 8 is located at each side from the upper side of the opening and extends nearly to the bottom thereof.

A member 9, substantially rectangular in shape, and of wood, preferably, has a back cover plate of sheet metal 10 applied thereto, being bent forward adjacent its upper and lower edges to fit against the upper and lower edges of the member 9. At the upper edge, the metal is off-set slightly for the insertion of the edge portions of a piece of fabric, or the like 11 thereunder, said fabric being folded longitudinally at its middle so as to make a projecting loop which projects forward of the front side of the member 9. Nails 12 and 12^a passed through the parts of the metal back 10 bent over the upper edges of the member 9 serve to fix said back in place, at the same time permanently attaching the part 11.

Under the back 10 and at the lower part of the member 9, a second sheet metal member 13 is located, it being formed with an in-

wardly extending U-shaped loop 14 which seats in a recess made in the back of member 9 transversely thereof. This loop 14 is made near the upper edge of the member 13 5 which, below the loop is extended to the lower edge of member 9 and then turned forward thereunder, being secured by nails 12^a at the same time the lower part of the back 10 is secured. A rod 15 lies in the loop 14 10 and in front of the back 10, at its ends extending beyond the sides of the member 9, each end of the rod being turned forward at right angles, as indicated at 16. The arms 16 thus formed are inserted in the back of 15 the front 4 of the refrigerator at each side of the door opening, as shown in Fig. 4. The rod 15 is located near the lower edge 20 of the member 9 so that but a relatively short portion of said member extends below the rod when the member is in vertical position 25 in the refrigerator (see Fig. 2). A recess, indicated at 17 is provided for the reception of the lower end of the member, in front of which is an upwardly projecting ledge 18. When the door 6 is opened, and the member 30 turned forwardly to substantially horizontal position, the member 9 bears against the upper edge of this ledge which serves as a solid abutment therefor, making a firm rest so that the member, in conjunction with the 35 relatively strong rod 15, is amply strong to withstand the weight, shocks and jars which come from placing the ice therein as it is being put into the ice compartment, as illustrated in Fig. 1.

When the ice is in the compartment, the member is elevated to vertical position, its back, adjacent its vertical edges coming 40 against the inwardly projecting vertical ribs 8 and the front side of the member 9 at its lower portion coming against the back of the ledge 18. At the same time, the back plate 7 of the door bears against the loop 11, as shown in Fig. 2. It is apparent that in this 45 position the cold air from the ice chamber is entirely cut off and insulated from the lower part of the door and that none of it can escape at the lower edge of the door or at the lower portions of the vertical side edges of the door. This is a very valuable 50 feature, particularly where refrigerators are used in places having humid atmospheres, cold air escaping downwardly, as is its natural tendency, past the lower edges of 55 the ice chamber door, serving to condense moisture from the air on the front of the refrigerator door, which is injurious to the finish of the refrigerator and destructive to glued joints. Moreover, in many refrigerators, below the ice chamber door there is 60 another door for entrance into a lower provision compartment, and the condensation and accumulation of moisture immediately above such additional door is very undesirable 65 occurrence, causing such door to swell

and stick in its door opening, and also being destructive to the door and the joints in the front of the refrigerator adjacent the door opening.

In addition, the member, when in horizontal position, as shown in Fig. 1 serves as a protector against chips or small pieces of ice lodging at the lower part of the door opening, and facilitates the entrance of the ice into the ice chamber. This construction is 70 very practical, can be manufactured with little additional cost, is durable, and in the course of very severe practical test has proved fully capable of sustaining all of the 75 claims of advantage above stated. The 80 claims appended define the invention, and all forms of construction coming within their scope are to be considered as comprehended by the invention.

We claim:

1. In a refrigerator construction, an ice chamber having a front thereto provided with a door opening, a door adapted to close the opening, a member pivotally mounted to turn on a horizontal axis to either vertical or substantially horizontal position, said pivotal axis being located at the lower side of the door opening, an inwardly extending vertical rib at each side of the door opening against which said member bears when in vertical position, and yielding means at the upper edge of the member to bear against the back of the door when the door is closed and the member is in vertical position, the lower portion of said member below its pivot bearing against the rear side of the front of the refrigerator below the door opening when said member is in vertical position.

2. In a refrigerator construction, an ice chamber having a front thereto provided with a door opening, a door for closing the opening, a member pivotally mounted back of the door and adjacent the lower portion of and within the opening to turn to either vertical or substantially horizontal position, in horizontal position bearing against the lower edge of the door opening and being supported thereby to serve as a support for the passage of ice thereover to the ice chamber, an inwardly vertical extending rib at each side of the door opening against which said member bears when in vertical position, yielding means at the upper edge of the member extending forward therefrom to bear against the back of the door when the door is closed and the member is in vertical position, said member having a portion extending below its pivot when in vertical position and bearing against the rear portion of the front of the refrigerator below the door opening.

3. In a refrigerator construction, an ice chamber having a front thereto provided with a door opening, a door for closing the opening, a member having a width substan-

- tially equal to the width of the door opening and a height less than the opening pivotally mounted to turn on a horizontal axis located between the vertical sides of the door opening back of the door and adjacent the lower edge thereof, a vertical rib extending inwardly from each vertical side of the door opening against which said member bears when in vertical position, said member when 10 turned to horizontal position bearing against the lower side of the door opening and forming a support for the ice passed into the ice chamber, and means at the upper edge of said member against which the rear side of 15 the door engages when said member is in vertical position and the door is closed.
4. In a refrigerator construction, an ice chamber having a front provided with a door opening having a horizontal ledge at its 20 lower side and a recess back of the ledge, a member having a width substantially equal to the width of the door opening, means for

pivottally mounting said member to turn on a horizontal axis at a point slightly above and back of said ledge whereby when in vertical 25 position the front side of the member at its lower portion bears against the rear side of the ledge and that portion of the member below its pivot is received in said recess and when in horizontal position rests against 30 said ledge, a vertical rib at each side of the door opening projecting inwardly therefrom against which the inner side of said member bears when in vertical position, and yielding means at the upper end of the member 35 against which the rear side of the door bears when the door is closed and said member is in vertical position, substantially as described.

In testimony whereof we affix our signatures.

HARRY C. LEONARD.
ALBERT TANGENBERG.
